UNITED STATES PATENT OFFICE

EUGENE G. REISING, OF EAST HARTFORD, CONNECTICUT, ASSIGNOR OF ONE-FOURTH TO
ALVA C. WASHBURN, OF PITTSFIELD, MASSACHUSETTS

FIREARM

Application filed November 23, 1928. Serial No. 321,492.

My invention relates to that class of firearms that are commonly supported at arm's length with the butt resting against the shoulder when being fired, and an object of my invention, among others, is to provide a firearm of this class that shall be particularly simple in construction as well as effective in operation, the simplicity of construction enabling the firearm to be produced at an extremely low cost.

One form of firearm embodying my invention and in the construction and use of which the objects herein set out, as well as others, may be attained, is illustrated in the accompanying drawings in which—

Figure 1 is a view in side elevation of my improved firearm with the front end of the barrel and the back end of the stock broken off.

Figure 2 is a similar view, scale enlarged, and with parts broken away in central lengthwise section, the mechanism being shown as cocked.

Figure 3 is a view similar to Figure 2 but showing the firing mechanism in its uncocked condition.

Figure 4 is a view in horizontal lengthwise section through a portion of the firearm on a plane passing through the axis of the barrel, the upper end of the magazine being broken off.

Figure 5 is a detail side view of the guard.

Figure 6 is a bottom view of a portion of the receiver and the action yoke.

Figure 7 is a detail isometric view of the breech block.

Figure 8 is an isometric view of the front end of the receiver showing the action yoke projecting therefrom.

In the accompanying drawings the numeral 10 denotes the frame or receiver of my improved firearm that is formed of any suitable material. This receiver has a groove of uniform depth extending from end to end thereof, the opening of said groove being on the under side of the receiver. This enables the receiver to be produced in a very simple and inexpensive manner.

The trigger guard 11 is also formed of U-shape in cross-section, it being composed of

any suitable metal that is, in a manner similar to the receiver, grooved from end to end enabling it to be formed in a very economical manner. It is of a width substantially the width of the groove in the receiver into which groove it fits and is secured in any suitable manner, as by means of rivets or screws. Lugs 12 are formed on the side pieces of the trigger guard, these lugs being secured to the receiver in the groove therein. A block 13 is secured within the groove in the receiver at the front end thereof, rivets or screws being employed for the purpose of securing said block in place, and a barrel 14 is secured in an opening in the block in a manner common to firearm construction, as herein shown screw threads being employed for securing the barrel to the block. A stock 15 of any suitable material is secured to the rear end of the receiver or frame in any suitable manner, as herein shown a bolt 16 extending through the stock from its rear end and engaging a block 17 secured in the rear end of the groove in the trigger guard, and as shown in Figure 2 of the drawings.

A breech bolt 18 is mounted for sliding movement in a breech bolt chamber 19 constituted by the bottom of the groove in the receiver, the front end of the chamber being closed by the block 13 and the rear end by the lugs 12 and the stock 15. The breech bolt has an action lug 20 at its rear end projecting from its under side, said lug having shoulders to rest upon the upper edges of the side parts of an action yoke that in turn rests upon the upper edges of the sides of the trigger guard for sliding movement thereon. A groove 21 is formed in the bottom of said lug to receive a pin 22 connecting the rear ends of the branches 23 of said action yoke, which yoke comprises a cross piece 24 at the front end thereof uniting said branches. The action yoke extends from within the chamber 19 through suitable openings at the front thereof to the outside and underneath the barrel 14, said openings being formed by reducing the width of the lower part of the block 13 thereby locating shoulders on said block spaced from the upper edges of the sides of the trigger guard and as shown in

Fig. 8. A forepiece 25 is secured to the front end of the frame or receiver in any suitable manner and a spring supporting rod 26 projects into the end of said forepiece and 5 through a hole in the cross piece 24 of the action yoke and into the block 13. An action spring 27 is supported on said rod and thrusts against the cross piece 24 at its front end and against a pin 28 extending through the rod 10 at its rear end, and as shown in Fig. 6 of the drawings.

A magazine 29 is insertable into a magazine chamber through a hole in the bottom of the trigger guard and within the breech bolt 15 chamber 19. A magazine catch 30 of any suitable construction may be employed to engage a notch in the front edge of the magazine to hold it in place.

A hammer 31 is pivotally mounted between 20 the side parts of the trigger guard and is urged forward to its striking position as by means of a spring 32 mounted on a firing rod 33 pivotally attached to the rear end of the hammer and extending backwardly through 25 the block 17, and as shown in Figure 3 of the drawings.

A sear 34 is pivotally mounted between the side parts of the trigger guard and is of peculiar construction, having an angular recess 35 in its side within which a disconnector 36 is located. This disconnector is pivotally attached to the upper end of a trigger guard, extending forwardly in line with the sear and then being bent around the sear and 35 extending through the recess 35 and upwardly therein. The upper end of the disconnector is positioned to engage within a notch 37 in one of the branches of the action yoke, and as shown in Figs. 2 and 3 of the 40 drawings, when said yoke is in its forward position. When thus engaged in said notch the bend in the disconnector will engage the back edge of the sear and a pull upon the trigger will thereby disengage the sear from 45 the hammer. When, however, the action yoke is in its rearward position, as shown in Fig. 2, the disconnector is forced downwardly and the bend therein will not engage the back of the sear if the trigger be pulled, 50 and it will therefore at this time be impossible to disengage the sear from the hammer. The sear is thrust toward the hammer by means of a sear spring 39, the upper back edge of the sear being shaped with an edge 55 to engage notches in the hammer in a manner common to firearm construction generally. The disconnector 36 is forced upwardly by means of a disconnector spring 40 and the trigger is forced forward by a trigger 60 spring 41.

The breech bolt 18 has grooves 42-43 formed in opposite sides thereof, a firing pin 44 being located in one of said grooves and an extractor 45 being located in the opposite 65 groove. The firing pin and extractor co-op-

erate in extracting a cartridge shell in a manner common to firearms of prior construction, and as shown in Fig. 4 of the drawings. In this structure, however, a tail 46 is formed extending laterally from the back end of said pin and a spring 47 is arranged to exert its force against the beveled end of the extractor 45 and against the tail 46, as shown in Fig. 4, for the purpose of normally holding the firing pin in its rearward position and for normally forcing the extractor in position to engage its nose with the rim of a cartridge shell, the spring 47 therefore serving a double function.

It will be noted that by thus constructing 80 the parts the firing pin may be stamped out from a flat piece of metal as may also the extractor and the formation of the grooves in the breech bolt to receive these flat elements greatly simplifies the construction both of the 85 means in the breech bolt for receiving the elements and in the structure of such elements.

It will be noted that throughout the entire structure I have made use of parts that are formed from flat metal and that the openings in different members are grooves which may be readily made at a minimum expense within the members in which said parts are 90 to be located.

I claim—

1. A firearm including a receiver having a breech bolt chamber therein, a breech bolt slidably mounted in said chamber, an action yoke comprising a separate strap of sheet metal of uniform thickness formed into 100 U-shape, means uniting the free ends of the side pieces of said yoke to removably engage said breech bolt, and a spring located between said side pieces to force the action yoke forward.

2. A firearm including a receiver having a breech bolt chamber therein, a breech bolt slidably mounted in said chamber, an action yoke comprising a separate strap of sheet metal of uniform thickness formed into 110 U-shape with a hole through the bend thereof, a rod extending through said hole and between the side pieces of the yoke, and a spring mounted on said rod between said side pieces to force the action yoke forward.

3. A firearm including a trigger with a support therefor, said trigger having a groove cut across its upper end, a disconnector pivotally mounted in said groove, and projecting forwardly from the trigger, a sear spaced from said trigger and engaged with said disconnector for operation thereby in one position of said disconnector, and a hammer to be engaged by said sear.

4. A firearm including a trigger with a 125 support therefor, a sear having an opening, a trigger to be engaged by said sear, a disconnector pivotally attached to said trigger and extending forwardly therefrom and having an upwardly projecting part, said 130

disconnector extending through said opening, and an action yoke in engagement with said disconnector and arranged to place said disconnector in an inoperative position in one position of said action yoke.

5. A firearm including a trigger with a support therefor, a sear having an angular shaped groove in one side, a disconnector of angular shape pivotally attached to said trigger and extending through said groove, said disconnector being adapted to engage said sear in one position of the disconnector, a hammer to be engaged by said sear, and an action member engaged with said dis-
10 connector and arranged in one position to hold the disconnector in an inoperative position.

15 6. A firearm including a breech bolt having grooves in its opposite edges, a firing pin located in one of said grooves, an ex-
20 tract or located in the other groove, a firing pin tail extending across the back of the breech bolt, and a spring positioned to exert its force against said extractor and
25 against said tail.
